Application May 17, 1933, Serial No. 671,480

15 Claims. (Cl. 230—21)

This invention relates to variable capacity compressors.

More particularly, this invention relates to capacity varying means whereby the capacity of constant speed compressors may be varied exactly in response to variations in the demand for compressed fluid.

Certain objects of my invention are to provide any one, or all of the respective compression compartments of any arrangement of single or multiple stage fluid compressors for compressing air or gas in either pressure or vacuum operation, with means to continuously and gradually vary the clearance volume supplemental to the normal clearance volume, to consequently vary inversely the capacity delivered and power required, exactly with variations in demand, by infinitesimally small degrees, by an infinite number of slight or imperceptably minute additions or reductions, progressively increasing as by increments, or progressively decreasing as by decrements, the said supplemental clearance volume, and inversely, the delivered capacity and power, to continuously effect slight or insensible changes in the same with changes in demand, all of which may be characterized by gradual slopes or curves.

Other objects, according to my invention, are to provide capacity varying and regulating means which gradually vary the capacity exactly in accordance with variations in demand within limits ranging from 100% of the full rated normal capacity down to zero capacity as above described, and vice versa, or, to gradually vary the capacity between the limits of fractional capacities, or, by dividing the supplemental clearance volume into fractions of predetermined volumes and by gradually varying one fractional part of the said supplemental clearance volume in periodic cycles to gradually vary the total effective volume of the same and the total supplemental clearance volume over the full range of variation, or, to gradually vary the capacity from the full rated capacity down to any predetermined minimum capacity, followed if desired, by complete unloading to zero capacity.

Also, according to my invention, I provide automatic means for continuously controlling and operating the said capacity and power varying means in response to variations in a physical condition such as fluid pressure of the air or gas, or, temperature as in a process.

According to my invention, many advantages result from exactly supplying continuous variations in demand by continuously varying the supplemental clearance volume, and therewith the

capacity, and required power, to continuously effect slight or insensible changes, which may be characterized by gradual slopes or curves, such as true variable capacity, smoothness of operation, efficiency, elimination of sudden changes in torque and load on the motor, elimination of pulsations and surges in the air or gas lines, and in the electric supply lines to the motor operating the compressor, as compared with the prior art means which solely and intermittently change the delivered capacity and proportionate power by a limited finite number of steps as by a plurality of means for step by step loading and unloading of a compressor by relatively large predetermined fractional percentages of its full rated capacity, arranged in step by step control, each acting to control a partial loading and unloading of the compressor.

Other objects and features of my invention will be more fully set forth in the following detailed description and accompanying drawings, in which,—

Figure 1 is a side elevation of one form of my invention, partially in vertical central section terminating at the inlet and discharge openings.

Fig. 2 is a plan view taken from Fig. 1, and shows a partial central horizontal section of a compressor cylinder, clearance varying means and interconnecting passages.

Fig. 3 is a side elevation partially in vertical section, and shows one form of clearance varying means and control and regulating means with interconnecting passages.

Fig. 4 shows a modification of the arrangement shown in Fig. 3.

Figs. 5 and 7 are side elevations of the compressor shown in Figs 1 and 2 and shows one form of a complete assembly including a partial vertical section of one form of clearance varying means, electrical operating means, and a fluid responsive regulator.

Fig. 6 is a detail of a part of the operating means for the clearance varying means shown in Figs. 5 and 7.

Fig. 8 is a detail showing a fluid pressure responsive governor operating an electric switch.

Fig. 9 shows a modified form of supplemental clearance volume control, and Figs. 9 and 10 show details of supplemental clearance volume which may be used in connection with the control shown in Fig. 11.

Fig. 12 shows a detail of a modified arrangement of the supplemental clearance volume control which may be used in connection with the arrangements shown in other figures.

Referring to Figs. 1 and 2, a single cylinder, single stage, double acting, direct connected, motor driven compressor is shown in which 1 is the cylinder, 2 is the head end head plate, and the 5 crank end head plate 3 which are bolted together and to the frame 4 in accordance with standard practise. In the description which follows, reference to bolts obviously needed to bolt together standard parts will not be made. The crank shaft 5 is supported at one end by bearings in the frame 4, and at its opposite end by an out-board bearing in accordance with the usual practise. The motor 6 is mounted directly on the crank shaft 5 and furnishes the power for operating the compressor by way of rotating the crank 7 which is fixedly attached to the crank shaft 5 with the key 8. The crank pin 9 is also fixedly attached to the crank 7 and is rotated by the crank shaft 5. The connecting rod 10 transmits motion from the crank pin 9 to the crosshead 11 which reciprocates the piston rod 12 and the attached piston 13. The piston 13 is provided with the usual piston rings 14, and 15 to reduce the leakage of air or gas past the piston 13 to a minimum as it is reciprocated in the cylinder 1.

The inlet pipe opening 16 connects with the chamber 17 from which the inlet stream of fluid to be compressed is divided to alternately pass 30 through the respective inlet passages 18, 19 leading to the inlet valve chambers 20, 21 respectively. The inlet valve 22 is shown positioned in the head plate 2 and held in place by the bonnet 24 and the stud 26. The inlet valve 23 is shown 35 positioned in the head plate 3 and held in place by the bonnet 25 and the stud 27. Preferably, I employ automatic inlet valves 22, and 23 of the standard plate type of construction which depend for their opening and closing entirely upon 40 pressure differences so as to admit air or gas to the cylinder 1 through the heads 2, and 3, and to prevent its return from the cylinder 1 when being compressed.

The discharge valves 28, 29, are also preferably of the standard construction plate type of automatic valves positioned respectively in the heads 2, 3 and retained in position by the bonnets 30, 31 and the studs 32, 33, respectively. The discharge valve 28, connected with the valve 45 chamber 34 and the passage 36, and the discharge valve 29, connected with the valve chamber 35 and the passage 37, join in the compartment 38 to which the discharge pipe 39 is attached. The discharge valves 28, 29, are provided to automatically permit the discharge of compressed air or gas from the cylinder 1 after 50 its pressure has slightly exceeded that in the discharge line 39, and to prevent its return on the suction stroke of the piston 13. The discharge valve 28 is provided with the seat section 40 and the guide section 41 so as to control its limits of movements when opening and closing. The discharge valve 29 is similar in construction to the discharge valve 28. The inlet valves 22, 23 55 are preferably similar in construction to the discharge valve 28, but positioned so as to operate in reverse direction of travel of fluid to that in the discharge valves 28, 29.

For cooling the parts, I provide the water jacket 42 in the head plate 2, the water jacket 43 in the cylinder 1, and the water jacket 44 in the head plate 3.

When the face 45 of the piston 13 is at or near its extreme position of travel toward the head plate 2 there will be a space between the piston

face 45 and the head plate 2, which together with spaces adjoining the inlet valve 22 and the discharge valve 28 is termed the normal clearance volume at the head end of the cylinder 1. Likewise, there will be a clearance volume or space between the face 46 of the piston 13 and the head plate 3, the inlet valve 23 and the discharge valve 29 when the piston 13 has travelled to its extreme position at the crank end of the cylinder 1 which is termed the normal clearance volume at the crank end of the cylinder 1. In each of these clearance volumes, there remains an unexpelled charge of compressed fluid after the normal delivery of the compressed fluid has been completed at or near the end of each stroke 15 of the piston 13.

The trapping of some of the compressed fluid in the clearance volumes, when re-expanded to inlet pressure, is equivalent to a certain amount of free air or gas at inlet conditions which is not 20 delivered by the compressor. This re-expansion of the unexpelled compressed fluid which remained in the clearance volumes consumes a portion of each return stroke of the piston before the pressure in the cylinder has become reduced 25 to permit the opening of the inlet valves which depend for their opening upon pressure differences. This clearance volume expansion causes a delayed opening of the inlet valves which reduces the quantities sucked into the cylinder to 30 be compressed when compared to the piston displacement or the volume displaced by the net area of the piston. The ratio between net delivery and piston displacement determines the volumetric efficiency of the compressor.

According to well known and well understood equations characterizing the phenomena of the compression of air and gases, the volumetric efficiency of a compressor and consequently the quantity taken in during a suction stroke at 40 standard inlet conditions, depends upon three variables, viz., the ratio of compression, or ratio of the absolute discharge pressure to the absolute inlet pressure, the percentage of clearance, and the exponent of the equation. The exponent is a constant for any particular gas, so it 45 can be disregarded. The ratio of compression is a constant for the condition of constant inlet and discharge pressures. Therefore, only one variable is left, and the volumetric efficiency, the 50 quantity sucked into the cylinder, and the delivered capacity, vary inversely with variations in the clearance. Increasing the clearance causes a smaller volume to be sucked in, and decreasing the clearance causes a relatively greater volume to be sucked into the cylinder. Also, according to the well known equations, aside from slightly greater possible leakage losses per 55 unit of capacity, hypothetically, the work and horse power per unit volume of air or gas sucked in, compressed and delivered, is independent of clearance, and varies directly with variations in the quantities sucked in, compressed and delivered, and therefore, with the capacity of the compressor.

As multi-stage compressors are subject in each stage to all of the characteristics of single-stage compression, the principles of my invention are equally applicable to both single-stage and multi-stage compressors.

Seldom is any compressor required to deliver continuously any particular fraction of its capacity for any considerable period of time. Hand regulation is not sufficient, is expensive and not dependable. A maximum demand for air or 70 75

gas can be provided for with either one large compressor, or with a number of relatively small compressors, the sum of the capacities of which equal the total maximum demand capacity. The 5 large single compressor of the conventional prior type with step by step control, and step by step loading and unloading, effects variations in capacity by relatively large predetermined percentages of its full rated capacity, each acting 10 to control a partial loading and unloading of the compressor the same as if a number of relatively small compressors were cut into and out of service. Such an arrangement supplies either 15 too much capacity, or not enough capacity, thus causing severe fluctuations in regulation and in the pressure in the supply and delivery pipes, severe fluctuations in the demand for power, and a relatively high cost of operation.

In the description of the various figures which 20 follow, like numerals denote similar parts, and only one detailed description will be given even though similar parts are frequently repeated in the figures which follow.

Referring to Figs. 1, 2, and 3, the passage 47 25 connects the interior of the cylinder 1 with the supplemental clearance volume represented by the cylinder 49, cooled by the water jacket 50. The passage 48 connects the interior of the cylinder 1 with the supplemental clearance volume 30 represented by the cylinder 51, cooled by the water jacket 52. The self operating piston 53, provided with the piston rings 54, 55, is fixedly attached to the rod 56, and reciprocates within the cylinder 49. Likewise, the self operating piston 57, provided with the piston rings 58, 59, is fixedly attached to the rod 60, and reciprocates within the cylinder 51. The piston 53 is provided with the extension 61 to give a damping effect when entering the recess 62 of the head plate 63. The piston 51 is provided with the extension 64 to give a damping effect when entering the recess 65 of the head plate 66. The rod 56 extends beyond the gland 67 of the stuffing box 68, and likewise, the rod 60 extends beyond the gland 69 of the stuffing box 70. The double purpose pistons 53, and 57, are shown respectively in their extreme positions of outward travel thus effecting the maximum available additions of the respective supplemental clearance volumes of the cylinders 49, 55 and 51, to the normal clearance volumes at the respective opposite ends of the cylinder 1. As the piston 53 is moved toward the head 63, the effective volume of the supplemental clearance 55 in the cylinder 49 is gradually reduced until the limit is reached at zero value of supplemental clearance volume by the closing of the passage 47 with the piston 53 as it approaches the head 63 as a limit of its travel. Likewise, as the piston 51 is moved toward the head 66, the effective volume of the supplemental clearance in the cylinder 51 is gradually reduced until the limit is reached at zero value of supplemental clearance volume by the closing of the passage 48 60 by the piston 57 as it approaches the head 66 as a limit of its travel.

A pilot valve 71, provided with the central passage 72, is housed within the body 73, and is operated by the rod 74, which passes through the head 75 which, with the stuffing box 76, closes the valve body 73 at its upper end, the lower end of which is closed with the head 77. The lower head 71 of the body 73 is connected with the lower head 78 of the cylinder 49 with the pipe 79. Fluid under pressure, such as air

or gas may be supplied through the pipe 80 from the discharge pipe 39, or, it may be supplied by the auxiliary operated compressor or liquid pump as at 81, which may be driven directly from the crank shaft 5, or, by the electric motor 82, energized by the leads 83, 84, and connected to the auxiliary unit 81 by the shaft 85, and both mounted upon the common base plate 86. The unit 81 is supplied with low pressure fluid through the tank 87 and the pipe 88, and the discharge 10 from the unit 81 is connected to the pipe 80 with the pipe 89, and interconnecting fittings as shown. The discharge pipe 89 of the unit 81 may also be connected by the pipe 90 with the pressure tank or accumulator 91 to receive and maintain a supply of excess fluid supplied by the unit 81, after which, further excess fluid over the normal needs may be discharged through the pipe 92, the relief valve 93, and the pipe 94 to the tank 87. The floating lever 95 is connected at its 20 one end by the pivoted pin 96 with the rod 56, and intermediate its ends it is connected by the pivotal pin 97, the rod 98, and the pivoted pin 99, with the rod 74, and the pilot valve 71. By moving the floating lever 95 manually or automatically, by giving motion to the pivotally mounted pin 100 about the fulcrum pin 96, the pilot valve 71 is moved accordingly. In the position as shown, the pilot valve 71 is moved to permit a slight flow of fluid from the pipe 80, 30 which flows through the central passage 72 and the pipe 79, to move the piston 53 and its attached rod 56 away from the head 78 in the direction of the head 63 to gradually reduce the supplemental clearance between the piston 53, 35 and the end of the cylinder 1 served by the passage 47, while at the same time, the rod 56 moves the pivotally mounted pin 96 and this end of the floating lever 95 about its fulcrum pin 100 to close the opening to the pipe 80, and prevent 40 further flow of fluid from the pipe 80 and to lock the piston 53 in a new position as there is now no flow either into or out of the cylinder 49 through the pipe 79. By lifting the pin 100 and its end of the floating lever 95, the pilot valve 45 71 is also lifted, and communication is established between the pipe 79 and the pipes 101, 102, and 94, so that the pressure developed in the cylinder 1 by the movement of the piston 13 pushes the piston 53 to cause a movement of the 50 piston 53 toward the head 78, and a flow of fluid through the pipe 79, the valve body 73, and pipes 101, 102, and 94 to the overflow tank 87, while at the same time, the downward movement of the rod 56, and the pivotally mounted pin 96, 55 and this end of the floating lever 95 also lowers the pilot valve 71 and again closes both of the pipes 80, and 101, thus locking the piston 53 in another new position depending upon the position of the pin 100. Similarly, the pilot valve 60 103, having the central passage 104 is housed within the valve body 105 and operated by the rod 106, which passes through the head 107 which, with the stuffing box 108, closes the valve body 105 at its upper end, the lower end of which 65 is closed with the head 109. The lower head 109 of the body 105 is connected with the lower end of the head 110 of the cylinder 51 with the pipe 111. Fluid under pressure is supplied by the pipe 112 which connects with the pipe 80, and 70 the overflow, or exhaust, may take place through the pipe 113 which connects with the pipe 102 and the tank 87. The floating lever 114 is connected at its one end by the pivotally mounted pin 115 with the rod 60, and intermediate its 75

ends, it is connected by the pivotally mounted pin 116, the rod 117 and the pivotally mounted pin 118 with the rod 106 and the pilot valve 103. By moving the floating lever 114 manually, or automatically, by giving motion to the pivotally mounted pin 119 about the fulcrum pin 115, the pilot valve 103 is moved accordingly. In the position as shown, the pilot valve 103 is moved to permit a slight flow of fluid from the pipe 112 which flows through the central passage 104 of the pilot valve 103, and the pipe 111 to move the piston 57 and its attached rod 60 away from the head 110 in the direction of the head 66 to gradually reduce the supplemental clearance volume between the piston 57 and the end of the cylinder 1 served by the passage 48, while at the same time, the rod 60 moves the pivotally mounted pin 115 and this end of the floating lever 114 about its fulcrum pin 119 to close the opening to the pipe 112 and prevent further flow from the pipe 112 and to lock the piston 57 in a new position, as there is now no flow either into, or out of the cylinder 51 through the pipe 111. By lifting the pin 119, and its end of the floating lever 114, the pilot valve 103 is also lifted, and communication is established between the pipe 111 and the pipes 113, 102, and 94, so that the pressure developed in the cylinder 1 by the movement of the piston 13 pushes the piston 57 to cause a movement of the piston 57 toward the head 110, and a flow of fluid through the pipe 111, the valve body 105, and pipes 113, 102, and 94, to the overflow tank 87, while at the same time, the downward movement of the rod 60, and the pivotally mounted pin 115, and this end of the floating lever 114 also lowers the pilot valve 103 and again closes both of the pipes 112, 113, thus locking the piston 57 in another new position depending upon the position of the pin 119. Accordingly, I have provided self operating, double purpose means for controlling the supplemental clearance volume, and for operating the said supplemental clearance volume varying means to gradually vary the same in one compression compartment, and also, in a plurality of compression compartments.

Any suitable physical condition governed means may be employed in connection with the means for regulating and controlling the operation of the supplemental clearance volume gradual varying means. In the present instance, a fluid pressure governed means is employed, and comprises a vertical cylinder 120, mounted upon the bracket 121, a plunger 122 fitted in the lower end of the cylinder 120, a weighted sleeve 123 fitted and movable vertically on the cylinder 120, a spring 124 interposed between the plunger 122 and the upper end of the sleeve 123. The sleeve 123 may be adjustably weighted by the divided rings 125 to determine the pressure which the compressor is to maintain. The cylinder 120 is connected below the plunger 122 with the discharge pipe 39 by the pipe 126. The sleeve 123 is connected by the head 127, the pivotally mounted pin 128, the rod 129, the pivotally mounted pin 130, the angular rocker 131 pivotally mounted on the pin 132, supported by the bracket 133, the pin 134 and the rod 135, the pivotally supported pin 136 and the angular rocker 137 pivotally mounted on the pin 138 supported by the bracket 133, the pivotal pin 139, and the rod 140 to the floating lever 114 with the pin 119, and to the floating lever 95 with the pin 136, rod 141, pivotal pin 142, angular rocker 143 pivotally mounted on the pin 144 supported by the

bracket 133, pivotal pin 145, rod 146 and the pivotal pin 100. The floating levers 95 and 114 and associated mechanism and controls operated by them are thus arranged to be operated jointly by the fluid pressure governed regulator means and by the extent of movement of the supplemental clearance volume varying means above described, as the movements of the pins 128, 119 and/or 100 are the same. An increase in the pressure in the pipe 39 causes the pin 128 to rise, and with it, the pilot valves 103, 71, which in turn causes the pistons 53, 57, to drop and increase the volume of the supplemental clearance which in turn, decreases the delivered capacity of the compressor, while a decrease in the pressure in the pipe 39, causes the pin 128 to fall, and with it the pilot valves 103, 71, which in turn causes the pistons 53, 57, to rise, decrease the volume of the supplemental clearance, and increase the delivered capacity of the compressor. Accordingly, means are provided for moving, controlling the extent of movement, stopping, and locking the mechanism in positions corresponding to the movement of fluid pressure governed regulating means to gradually vary the supplemental clearance volume in response to gradual variations in demand, and in the pressure in, for example, the delivery pipe, in one compression compartment, or, in a plurality of compression compartments.

The pointer 147 is fixedly mounted upon any rod as for example, the rod 60, to cooperate with the scale 148 which is shown mounted upon the head 66, to indicate the capacity delivered by the compressor at all rates of delivery within the limits of variation, and with constant inlet and discharge pressures. The scale 148 may also read in percentage of clearance. The frame 149 may contain a curve sheet from which the actual capacity delivered may be read from the percentage of clearance and the ratio of compression calculated from the ratio of the discharge pressure read upon the pressure gage 150 connected with the discharge pipe 39 by the pipe 151, and the inlet pressure read from the pressure gage 152 connected with the inlet pipe 16 by the pipe 153, and corrected for temperature by readings from the thermometer 154 placed in the inlet pipe 16, as a result of the phenomena of compression and delivery as obtained in compressors constructed and operated according to my invention. Accordingly, means are provided not only to operate the supplemental clearance varying means, but also, to vary gradually the clearance volume supplemental to the normal clearance volume, means to control the extent of the said gradual variations of the said supplemental clearance volume, to consequently vary the delivered capacity and power with variations in demand, in response to variations in pressure, and means for indicating the same, all by an infinite number of slight or imperceptibly minute additions or reductions, progressively increasing as by increments, or progressively decreasing as by decrements, which may be characterized by gradual slopes or curves, in one compression compartment, or in a plurality of compression compartments.

Referring to Fig. 4, a modified operation of the pistons 53, 57 is shown. In this arrangement of my invention, the piston 53 is operated by the auxiliary piston 155, provided with the piston rings 156, 157, fixedly mounted upon the rod 56, and disposed within the cylinder 158, mounted upon the distance piece 159 which serves jointly as heads for the cylinders 49, and 158, and which is provided with the stuffing boxes 75

160, 161 and the stuffing box glands 162, 163 respectively. The pilot valve 164 is provided with the full diameter sections 165, 166, the reduced diameter section 167, and the central passage 168, 5 for operation in the pilot valve body 169, closed at its upper end with the head 170 and the stuffing box gland 171, and at its lower end with the head 172, and mounted upon the bracket 173. The pipe 174 is supplied with a source of fluid 10 under pressure as from the pipe 39, or from the pipe 89, and the pipes 175, 176 may either supply fluid under pressure or exhaust it, depending upon the position of the pilot valve 164. When the regulator pin 128 drops as a result of lowering 15 pressure in the pipes 39, 126, the pin 99 and the pilot valve 164 also drop to a position as shown, the floating lever 95 having moved about its fulcrum pin 96, and fluid is exhausted from the cylinder 158 through the pipe 175, the central passage 168 of the pilot valve 164, and the pipes 101, 102, while at the same time, fluid under pressure flows from the pipe 174 around the reduced diameter section 167 of the pilot valve 164, and through the pipe 176 to lift the piston 155, the rod 56 and the piston 53. Simultaneously, the piston rod 56 lifts the pin 96 and its end of the floating lever 95 about its new fulcrum pin 100 and lifts the pilot valve 164 to close the passages and pipes 175, 176, so no fluid flows 20 in either, and the piston 155, as well as the piston 53, are both locked in a new position. The lifting of the pistons 155, 53, decreases the supplemental clearance volume between the piston 53 and the end of the cylinder 1 served by the passage 48 which increases the 25 delivered capacity of this end of the compressor similar to the other end of the compressor, and thus, again builds up the pressure in the pipe 39. When the pressure in the pipe 39 rises, the pins 128, 118, and the pilot valve 164 rise, resulting in the flow of fluid under pressure through the 30 pipe 196, and the exhaust of fluid through the pipe 197, which lowers the pistons 171, 57, and the rod 60 and the end of the floating lever 114 with connecting pin 115 to again lock the pistons 171, 57 by way of closing the pipes 196, 197, from 35 communication with the pipes 195 and 113. The lowering of the piston 57 increases the supplemental clearance volume in the cylinder 51 between the piston 57 and the cylinder 1, and decreases the delivered capacity from this second 40 end of the plurality of compression compartments of the cylinder 1, to maintain the pressure in the pipe 39 substantially constant, and to limit its variations from the desired normal pressure to a relatively small difference.

Likewise, the piston 57 is operated by the auxiliary piston 177, provided with the piston rings 178, 179, is fixedly mounted upon the rod 60 and disposed within the cylinder 180, mounted upon the distance piece 181 which serves jointly as heads for the cylinders 51, 180, and which is provided with the stuffing boxes 182, 183, and the glands 184, 185 respectively. The pilot valve 186, provided with the full diameter sections 187, 188, the reduced diameter section 189, and central passage 190, operates in the pilot valve body 191, which is closed at its upper end with the head 192 and the stuffing box gland 193, and at its lower end with the head 194 which is mounted upon the bracket 173. The pipe 195 is supplied with fluid under pressure as from a source such as the pipe 39, or from the pipe 89, and the pipes 196, 197 may either supply fluid under pressure, or exhaust it depending upon the position of the pilot valve 186. When the regulator pin 128 drops as a result of lowering pressure in the pipes 39, 126, the pin 118 and the pilot valve 186 also

drop to a position as shown, the floating lever 114 having moved about its fulcrum pin 115, and fluid is exhausted from the cylinder 180 through the pipe 196, the central passage 190 of the pilot valve 186, and the pipes 113, 102, while at the same time, fluid under pressure flows from the pipe 195 around the reduced diameter section 189 of the pilot valve 186, and through the pipe 197 to lift the piston 171, the rod 60 and the piston 57. Simultaneously, the piston rod 60 lifts the pin 115 and its end of the floating lever 114 about its new fulcrum pin 119, and lifts the pilot valve 186 to close the passages and pipes 196, 197 so no fluid flows, and the piston 171, as well as the piston 57, are both locked in a new position. The lifting of the pistons 171 and 57 decreases the supplemental clearance volume between the piston 57 and the end of the cylinder 1 served by the passage 48 which increases the delivered capacity of this end of the compressor similar to the other end of the compressor, and thus, again builds up the pressure in the pipe 39. When the pressure in the pipe 39 rises, the pins 128, 118, and the pilot valve 186 rise, resulting in the flow of fluid under pressure through the pipe 196, and the exhaust of fluid through the pipe 197, which lowers the pistons 171, 57, and the rod 60 and the end of the floating lever 114 with connecting pin 115 to again lock the pistons 171, 57 by way of closing the pipes 196, 197, from communication with the pipes 195 and 113. The lowering of the piston 57 increases the supplemental clearance volume in the cylinder 51 between the piston 57 and the cylinder 1, and decreases the delivered capacity from this second end of the plurality of compression compartments of the cylinder 1, to maintain the pressure in the pipe 39 substantially constant, and to limit its variations from the desired normal pressure to a relatively small difference.

As the floating levers 95, 114, are moved simultaneously by the pins 128, 100, 119, and as the movements of the pistons 53, 57, 155, 177 are required to close the pilot valves 164, 186, and the pipes 175, 176, and 196, 197 respectively, the movements of the supplemental clearance control pistons 53, 57, and the supplemental clearance volumes will always be the same and equal in the arrangement as shown. Whereas, I have described the above arrangement for synchronous operation of the supplemental clearance volume varying means simultaneously, it will be understood that many combinations are possible by way of changing the positions and lengths of the pilot valve sections, and the positions of the service pipes as they enter or leave the pilot valve bodies, and by operating the pins 99, 118 selectively in slots arranged for operating the supplemental clearance piston 53 in sequence with the supplemental clearance piston 57 to effect either successive or selective operation of the same in which any or all supplemental clearance volume controls may either antecede or supplement any other control. Accordingly, I have provided means for operating and controlling a plurality of supplemental clearance volume varying means gradually and continuously in a plurality of compression compartments in response to variations in the movements of the fluid pressure governed regulating means, responsive to variations in the fluid pressure and in the demand, all of which may be characterized by gradual slopes or curves.

The passage 198, the coupling 199, and the passage 200 may be provided to interconnect the cylinder 49 with the cylinder 51 when the pistons 75

53, 57, as shown in Fig. 4 are in their extreme outward positions, to cause the air or gas to be circulated back and forth through the clearance cylinders 49, and 51, and the passages 47, 48, 5 from one end of the compression cylinder 1 to the other end to effect complete unloading to zero capacity. Accordingly, I have provided means for gradually varying the delivered capacity from the full rated capacity down to a predetermined 10 minimum delivered capacity by gradually varying the clearance volumes supplemental to the normal clearance volumes for each of the respective opposite ends of the cylinder 1 inversely with variations in demand, followed by complete unloading to zero delivered capacity without the requirement of additional valves such as pressure operated pistons, incidental cylinders and control mechanism for the same.

20 The piping 201, connected with the head 78, 20 may connect with the piping 202, connected with the head 110, and the piping 203, with the discharge pipe 39 to prevent the building up of pressure, or the formation of vacuum in the cylinders 49, between the piston 53 and the head 78, and 25 51, between the piston 51 and the head 110, in this arrangement of my invention to provide means for maintaining a relatively low net unbalanced 30 resistance against the pistons 53 and 57.

35 Referring to Figs. 5 and 6, an arrangement of my invention is shown in which electric power is used in the means for operating the supplemental clearance volume varying means, the control of which is similar to that used in the fluid pressure operated arrangements above described. In this 40 arrangement, the piston rod 56 is threaded as at 204 where it extends beyond the gland 205 of the stuffing box 206 formed into the head 207, and slotted as at 208 along the threaded section 204 to prevent rotary motion of the rod 56 as it 45 slides over the key 209, which is also mounted in the head 207. Likewise, the piston rod 60 is threaded as at 210 where it extends beyond the gland 211 of the stuffing box 212 formed into the head 213, and slotted as at 214 to prevent rotary motion of the rod 60 as it slides over the 50 key 215 which is mounted in the head 213. The internally threaded flanged collar 216 is disposed in the head 207, and retained in position by the head 217 and by the bearings 218, 219 which serve 55 as both bearings and as thrust bearings. Also, the internally threaded flanged collar 220 is disposed in the head 213 and retained in position by the head 221, and by the bearings 222, 223 which serve 60 as both bearings and as thrust bearings. The worm gear wheel 224 is fixedly mounted upon the flanged collar 216 and is operated by the worm 225 which is fixedly mounted upon the shaft 226 and retained in position by the head supports and 65 bearings 227, 228. The worm gear wheel 229 is fixedly mounted upon the internally threaded flanged collar 220 and is operated by the worm 230 which is fixedly mounted upon the shaft 231 and retained in position by the bearings and supports 232, 233. The shafts 226 and 231 are 70 interconnected by the pin coupling 234 so that the rods 56, 60, may move due to expansion or contraction of the compressor cylinder 1 without straining the parts or changing their angular relationship with respect to each other as they 75 are driven by the auxiliary reversible electric motor 235, which is mounted upon the bracket 236, and energized by the source of electric supply 237.

The floating lever 238, similar to the floating 75 levers 95, 114, is pivotally mounted upon the

rod 60 by the pin 239, and at its opposite end it is connected pivotally by the pin 240 to the rod 129 of the fluid pressure governed regulator previously described, and is again jointly operated and controlled by the movement of either or both of the two fulcrum pins at its opposite ends, in this case, the pins 239, 240. Intermediate to the ends of the floating lever 238, the pivotal pin 241 connects the floating lever 238 with the rod 242, the pivotal pin 243 and any suitable switching device 10 such as the rotary switch 244, pivotally mounted upon the pin 245, and suitably supported by the bracket 246. The insulated electric conducting bridge member 247 of the switch 244 may bridge over and complete an electric circuit between the contact arcs 248, 249, mounted upon the insulated member 250, or it may bridge over and complete an electric circuit between the contact arcs 251, 252, mounted upon the insulated member 253, and the insulated members 250, 253 may be adjustably mounted upon an extension 254 of the bracket 246 by the bolts 255. When the pressure in the pipes 39, 126 rises, the fluid pressure governed regulator lifts the pin 240 and its end of the floating lever 238 operating around the fulcrum point 239, and moves the conducting bridge 247 of the switch 244 to bridge over the arc contacts 248, 249, and completes an electric circuit from the source of electric supply 20 through the lead 256, switch 257, switch point 258, lead 259, contact 248, bridge 247, contact 249, lead 260, contact points 261, 262, of the spring operated limit switch 263, adjustably mounted upon the bracket 264 by the bolt 265, lead 266, clockwise rotation of the motor 235, lead 267 back to the source of supply 237. Clockwise rotation of the motor 235 rotates the shaft 231, coupling 234, shaft 226, worms 230, 225, worm gear wheels 229, 224, and internally threaded flanged collars 220, 216 respectively, thus causing 40 the rods 60, 56, and attached pistons 57 and 53 to slide so that the pistons 57, 53, recede from the heads 213, 207, and increase gradually the supplemental clearance volumes in the cylinders 51, 45 49, serving the cylinder 1 through the passages 48, 47 respectively, and gradually decrease the delivered capacity and power of the cylinder 1. At the same time such movement of the pistons 51, 53, and the rods 60, 56, are equal, as they 50 are geared together, causing the pin 239 end of the floating lever 238 to move about its fulcrum pin 240 and in turn move the switch 244 and attached bridge 247 to break the circuit between the contact arcs 248, 249 and stop further movement of the motor 235, pistons 57, 53, and interconnecting mechanism. Conversely, a drop 55 in pressure in the pipes 39, 126, causes a lowering of the pin 240 and its end of the floating lever 238, moving around the fulcrum point 239, and moves the conducting bridge 247 of the switch 244 to bridge over the arc contacts 251, 252, and completes an electric circuit from the source of electric supply 260 through the lead 256, switch 257, switch point 258, lead 259, lead 268, contact arc 251, bridge 247, contact arc 252, lead 269, spring operated limit switch 270, adjustably mounted upon the bracket 264 by the bolt 271, contact points 272, 273, lead 274, counter clockwise rotation of the motor 235, and lead 267 back to the 65 source of supply 237. Counter clockwise rotation of the motor 235 rotates the shaft 231, coupling 234, shaft 226, worms 230, 225, worm gear wheels 229, 224, and internally threaded flanged collars 220, 216 respectively, thus caus- 70 75 80 85 90 95 98

ing the rods 60, 56 and attached pistons 57, 53, to slide so that the pistons 57, 53, approach the heads 213, 207, and decrease gradually the supplemental clearance volumes in the cylinders 51, 49, serving the cylinder 1 through the passages 48, 47 respectively, and gradually increase the delivered capacity and power of the cylinder 1. At the same time, such movement of the pistons 57, 53, and the rods 60, 56, causes the pin 239 end 5 of the floating lever 238 to move about its fulcrum point 240 and in turn move the switch 244 and attached bridge 247 to neutral position and to break the circuit between the contact arcs 251, 252, and stop further movement of the motor 235, 10 pistons 57, 53, and interconnecting mechanism, following which repeated actions occur in the movements of the fluid pressure governor and the floating lever 238 to continuously control the direction of rotation and the duration of rotation of 15 the motor 235, the direction of travel, and the extent of travel of the pistons 57, 53 accordingly as will be understood, to gradually vary continuously the clearance volumes supplemental to the normal clearance volumes simultaneously and 20 equally in each end of the cylinder 1 in response to variations in pressure, caused by variations in demand, and to vary the delivered capacity and power gradually, progressively increasing the same as by increments, or, progressively decreasing 25 the same as by decrements, which may be characterized by gradual slopes or curves. Whereas, I have shown and described a plurality of controls serving a plurality of compression compartments, it will be understood that by disconnecting the coupling 234, the operation and 30 control of only the piston 57 will be effected in the single compression compartment of the cylinder 1 served by the passage 48. The floating lever 238 is provided with the extension 275 to 35 operate the arm 276 of the limit switch 263 and stop the motor 235 when the pistons 57, 53, have reached their most extreme outward position furthermore from the heads 213, 207 respectively, whereupon, there is now only one direction of 40 travel desired and that is toward the heads 213, 207, and this movement is obtained by reverse rotation of the motor 235, the extreme travel of which is limited by the cooperation of the extension 277 of the floating lever 238 which operates 45 the arm 278 of the limit switch 270 to stop the motor 235 and to prevent straining of the motor and driven mechanism. The limit switches 263, 270 may be adjustably positioned by the bolts 265, 271 respectively to limit the control of the 50 variation of movement of the supplemental control pistons 53, 57, to any desired limits of capacity variation delivered by the compressor cylinder 1. The switch 257 may be operated manually by the member 279, or automatically such as by an electromagnetic member 280, energized by the leads 281, 282, to render control by the fluid pressure responsive governor and the floating lever 238 55 uneffectual, and to unload the compressor completely by throwing the switch 257 from the switch point 258 to the switch point 283 to operate the auxiliary motor 235 in clockwise rotation and move the pistons 57, 53, to their extreme outward positions, and thus open the passages 198, 199, 200, to circulate fluid back and forth in the cylinder 1. After the motor 6 is ready, or again 60 ready to take the load, the switch 257 may be returned to the switch point 258 to again restore the automatic control by the fluid pressure regulator and floating lever 238.

75 Referring to Fig. 7, an arrangement is shown

of my invention which is similar in most respects to the arrangement shown in Fig. 5 and 6, but in which two pistons are disposed within each supplemental clearance control cylinder in lieu of the arrangement shown in Figs. 5 and 6. In the arrangement shown in Fig. 7, the cylinder 284, provided with the water jackets 285, is connected with the cylinder 1 by the passage 47, and the cylinder 286, provided with the water jackets 287, is connected with the cylinder 1 by the passage 10 48. The piston 288, provided with the piston rings 289, 290, is disposed within the upper end of the cylinder 284, and the piston 291, provided with the piston rings 292, 293, is disposed within the lower end of the cylinder 284. The piston 288 is 15 threaded in its central opening to fit and operate upon the threaded portion of the rod 294 between the midpoint 295 of the cylinder 284 and the passage 47 and the head 207, whereas, the piston 291 is threaded in its central opening to fit and operate upon the oppositely handed threaded portion of the rod 294 between the said midpoint 295 and the lower head 296, where the rod 294 is retained in position by the plate 297, the bearing 298, the collar 299 and the pin 300 which may fixedly 20 attach the collar 299 to the rod 294. The upper end of the rod 294 is fixedly attached to the flanged collar 301 by the pin 302. The rod 303 is retained in position by the heads 207, 296, and passes through the pistons 288, 291 in sliding fit- 25 relation to prevent rotation of the said pistons 288, 291, as the rod 294 is rotated in either clockwise or counter clockwise rotation to cause the pistons to approach and meet at the central point 295 as a limit of travel in this direction, a minimum of supplemental clearance volume, and a maximum delivered capacity of its compression compartment, or to recede oppositely from the central point 295 upon opposite rotation of the shaft 294, to gradually increase the supplemental 30 clearance volume and gradually decrease the delivered capacity up to the limit of variation obtained as the pistons 288, 291 approach the heads 207, 296, respectively, and vice versa. Likewise, the piston 304, provided with the piston rings 305, 306, is disposed within the upper end of the cylinder 286, and the piston 307, provided with the piston rings 308, 309, is disposed within the lower end of the cylinder 286. The piston 304 is threaded in its central opening to fit and operate upon the threaded portion of the rod 310 between the midpoint 311 of the cylinder 286 and the passage 48, and the head 213, whereas, the piston 307 is threaded in its central opening to fit and operate upon the oppositely handed threaded portion of the rod 310 between the said midpoint 311 and the lower head 312, and retained in position by the plate 313, the bearing 314, the collar 315 and the pin 316 which may fixedly attach the collar 315 to the rod 310. The upper end of the rod 310 is fixedly attached to the flanged collar 317 as by the pin 318. The rod 319 is retained by the heads 213 and 312 and passes through the pistons 304, 307, in sliding fitted relation to prevent rotation of the said pistons 304, 307, as the rod 310 is rotated in either clockwise or counter clockwise rotation to cause the pistons to approach and meet at the central point 311 as a limit of travel in this direction, a minimum of supplemental clearance volume, and a maximum delivered capacity of the compressor compartment, or to recede oppositely from the central point 311 upon opposite rotation of the shaft 310 to gradually increase the supplemental clearance volume and gradually decrease the delivered capacity up to the limit of 35 40 45 50 55 60 65 70 75

variation obtained as the pistons 304, 307, approach the heads 213, 312, after which, the compressor is completely unloaded when the pistons 288, 291, 304, 307, are adjacent the heads 207, 296, 5 213 and 312 respectively, thus opening the passages 320, 321, at the respective upper and lower ends of the cylinders 284, 286, and the opposite ends of the cylinder 1 to circulate air or gas back and forth through the passages 47, 48, between 10 the opposite ends of the cylinder 1. In addition to the operating of the worms 225, 230, and the worm wheels 224, 229, attached to the respective rods 294, 310 by the pins 302, 318 respectively, to 15 rotate the rods in either clockwise or counter clockwise rotation depending upon the direction of rotation of the motor 235, I provide as a part of the control mechanism, the worm 322 fixedly mounted upon the motor drive shaft 231, the driven worm gear wheel 323, and the rocker arm 20 324, both fixedly mounted upon the shaft 325, with the key 326, the shaft 325 being suitably supported by the bracket 321. The rocker arm 324 is pivotally connected by the pin 328, the rod 329, and the pivotally mounted pin 330 with the rod 331 25 which slides in suitable openings in the extensions 332, 333, of the bracket 321, and which in turn is pivotally connected with the floating lever 238 with the pin 334, thus giving motion to the pin, 334 and its end of the floating lever 238 in correspondence with reversals of direction of the motor 235, and in correspondence with the extent of movement and direction of movements of the 30 pistons 288, 291, 304, and 307.

Referring to Fig. 8 of my invention, the fluid pressure responsive governed regulator pin 128 35 is shown connected directly to the switch member 244 by the rod 129, and the pin 243 for use in connection with such arrangements as desired in combinations in which the floating lever features of 40 the particular control is not needed.

Referring to Figs. 9, 10, and 11, a modified form 45 of my invention is shown in which the supplemental clearance volume is divided into a number of variable and unvariable fractional divisional parts of the total, and in which the variable divisional part of the total is arranged to antecede the unvariable divisional parts of definite predetermined fixed volume, and then supplement each such unvariable fixed volume as successively 50 made effective, thus obtaining combinations of varying volumes which vary gradually to any requirement between the limits of zero volume and the total combined volumes of the variable and unvariable fractional divisions of the same, 55 progressively increasing as by increments, or progressively decreasing as by decrements, which may be characterized by gradual slopes or curves.

Referring to Fig. 9, the cylinder 335 may contain a piston 336, similar to the piston 57, and 60 be operated and controlled by the rod 337, similar to the rod 60, and be closed at its upper end by the head 338, similar to the head 213, and be connected to the cylinder 1 by the passage 339, similar to the passage 48. When the piston 336 65 moves from a position adjoining the head 338, it first uncovers the passage 339, and then successively, the passage 340 and the clearance pocket 341, passage 342 and a clearance pocket which is not shown but similar to the pocket 70 341, passage 343 and pocket 344, passage 345 and passage 346, each with a pocket which is not shown, passage 347 and pocket 348, passage 349 and pocket 350, passage 351 and a pocket not shown, all the said pockets being of predetermined fixed unvariable volume, and finally, the

passage 352 may interconnect with a similar passage in another cylinder to permit the complete unloading of the compression compartments so served, similar to that effected by passages 198, 199, 200, and passages 320, 321. 5

Referring to Figs. 10 and 11 of my invention, I provide in addition to the supplemental clearance volume cylinders 49, 51, the fixed, unvariable volume, supplemental clearance pocket 353, controlled by the valve 354, which is opened by the spring 355 and closed by the pressure of a fluid which flows through the pipe 356 acting to push the piston 357 to close the valve 354, and conversely, the exhaust of fluid through the pipe 356 permits the spring 355 to act and open 10 the valve 354. A valve, similar to valve 354, and fixed volume clearance pocket 358, similar to the pocket 353, are disposed within the housing 359 at the opposite end of the cylinder 1, and controlled by flow of, or exhaust of fluid through 15 the pipe 360, similar to the customary manner as used in the conventional type of compressors operating and controlled by the well known step by step clearance pocket control. According to my invention, the unvariable pocket 353 is antecedent in its operation by the continuous operation of the variable gradual varying supplemental clearance control cylinders 49, 51, and the pistons 53, 57, which are continuously operated to 20 gradually vary the volume of supplemental clearance from any amount to any other amount for small variations between the limits of zero volume and a volume equal to the volume of the unvariable pocket 353 which is next made effective, 25 and simultaneously, the variable supplemental clearance volume in the cylinders 49, 51, controlled by the pistons 53, 57, continuously supplement the volume of the unvariable volume pocket 353 from their zero volume, gradually adding supplemental clearance to the volume of 30 pocket 353, up to a volume equal to the additional volume of the pocket 358 which is next made effective, and simultaneously again, the variable supplemental clearance volume in the cylinders 49, 51 and controlling pistons 53, 57 supplement 35 from their zero volume the unvariable volume of the sum of the two fixed volume pockets 353, 358 by gradually increasing continuously the effective volume by volumes varying from zero 40 up to the maximum available volume of the variable divisional parts 49, 51, to gradually increase the clearance volume supplemental to the normal clearance volume of the cylinder 1 progressively increasing as by increments, and conversely, by 45 reverse operation effected by the control mechanism, progressively decreasing the said net total of all the supplemental clearance volumes as by 50 decrements, by decreasing the effective volume in the cylinders 49, 51, after which the pocket 358 is cut out of operation, then the effective 55 volume in the cylinders 49, 51 is again decreased, after which, the pocket 353 is cut out of operation, and then again, the effective volume in the cylinders 49, and 51 is gradually reduced from a volume equal to the volume of the pocket 353 60 by decrements, as required, to effect the correct supplemental clearance volume to deliver the desired capacity, down to the limit of zero volume and a maximum delivered capacity of the compressor. The operation of the fluid pressure 65 governed regulator and other similarly numbered parts, is the same as described by reference to the preceding figures of my invention. In this arrangement of my invention, the regulator controlled pin 128 is connected to the member 361 70

75

by the rod 129, and pivotally mounted pin 362, to move the member 361 pivotally about its supporting pin 363 which in turn is mounted upon the bracket 364 and the compressor frame 4. The member 361 is provided with the slot 365 which cooperates with the pin 366 attached to the rod 367, to operate the interconnecting pin 368, the rod 369, and attached pilot valve 370, by compressing the returning spring 371, operating between the head 372 and the pilot valve 370. Also, the member 361 is provided with the slot 373 which cooperates with the pin 374, attached to the rod 375, to operate the interconnecting pin 376, the rod 377, and attached pilot valve 378 by compressing the returning spring 379, operating between the head 372 and the pilot valve 378. The member 361 also operates the periodic cyclical cam 380 in rotational movement about the pin 381, suitably supported by the bracket 382, and the frame 4, through the rod 383, and the pivotally mounted pins 384, 385. The periodic cyclical cam 380 is therefore moved in response to movements of the fluid pressure governed regulator pin 128. When the pressure in the pipes 39, 126, is the lowest, the pin 128 is in its lowest position, and the roller 386, pivotally mounted in rolling relationship with the floating lever 238, by the pin 387, rests upon the smallest radial part of the section 388 of the cam 380, thus effecting a bridging over of the contact arcs 251, 252, by the bridge 247, counter clockwise rotation of the motor 235, and a reduction of the supplemental clearance volume in the cylinders 49, 51 to zero, thus increasing the delivered capacity of the cylinder 1 to its maximum capacity. Such maximum delivered capacity increases the pressure in the pipes 39, 126, and causes the fluid pressure governed pin 128 to gradually rise, effecting a clockwise rotating movement of the member 361, counter clockwise rotating movement of the cam 380, and a gradual increasing in the effective length of the radii of the cam section 388, and a gradual lifting of the roller 386, and its end of the floating lever 238 to gradually increase the clearance in the cylinders 49, 51, to effect a balance between delivered capacity and demand, which is reflected by the pressure in the pipes 39, 126. As the pressure in the pipes 39, 126 continues to rise, the cam 380, and the member 361, continue to move to increase the supplemental clearance volume in the cylinders 49, 51, to their maximum volume, reached when the roller 386 is rolling upon the greatest length radius of the section 388 of the cam 380, whereupon simultaneously, the member 361 in cooperation with the slot 365, and the pin 366, picks up the movement and lifts the pilot valve 370 to bring into place its reduced diameter section 389 to effect communication between the pipes 356 and 390, to cause exhaust of fluid from above the piston 357, and the valve 354 to open, and make effective the unvariable supplemental clearance volume of the pocket 353, and the roller 386 has dropped to the shortest radius of the cam section 391, and reduced the effective volume of the supplemental clearance cylinders 49, 51 again to zero value for the instant, following which, the cam 380 continues to move further in response to further upward movement of the governor pin 128 to gradually increase the effective supplemental clearance volume in the cylinders 49, 51, to gradually decrease the delivered capacity from the cylinder 1, progressively as by decrements up to the limit of capacity reduction effected by the section 391 of the cam 380, when simultaneously, the member 361, in cooperation with the slot 373, and the pin 374, picks up the movement, and lifts the pilot valve 378 to bring into place its reduced diameter section 392 to effect communication between the pipes 360 and 390, to cause exhaust of fluid from controlling a piston similar to the piston 357, which also makes effective the volume of the unvariable supplemental clearance volume of the pocket 358, and again, the roller 386 has fallen to the shortest radius of the cam section 393, and reduced the effective volume of the supplemental clearance cylinders 49, 51, to a zero value for the instant, and a total effective volume represented by the sum of the volumes of the pockets 353, 358, following which the cam 380 continues to move further in response to further upward movement of the governor pin 128 to gradually increase the effective supplemental clearance volume in the cylinders 49, 51, to gradually decrease the capacity delivered from the cylinder 1 until the limit of minimum delivery is reached with maximum available total effective supplemental clearance volume. Conversely, with a falling pressure in the pipe 39, 126, the effective volume of the cylinders 49, 51, is gradually reduced to their zero value, then the pocket 358 is made uneffective by the flow of fluid through the pipe 394, and pipe 360, and the volume of the cylinders 49, 51, is again a maximum for the instant, then gradually decrease to zero value, when the pocket 353 is made uneffective by the flow of fluid through the pipe 394, and the pipe 356, and the volume of the cylinders 49, 51 is again made a maximum, after which the effective volume of the cylinders 49, 51, is gradually reduced until the limit is reached at zero value when the maximum delivered capacity of the compressor cylinder 1 is again effective. Thus, the capacity, and power, are varied progressively as by increments, or progressively as by decrements, exactly to any requirement between the limits of the maximum and minimum capacity in response to variations in the pressure, effected by varying the effective volume of the supplemental clearance progressively as by decrements, or progressively as by increments, exactly to any requirement between the limits of minimum and maximum effective supplemental clearance volume, and vice versa. It will be understood that in the particular arrangement of variation of the variable and unvariable supplemental clearance volumes, the operating of the unvariable volumes by fluid pressure, and the operating of the variable volumes by electric power is merely for the purpose of illustrating and describing one combination, and that many other combinations are possible in accordance with the principles of my invention.

In this arrangement of my invention, the pointer 395, suitably attached to the member 361, is similar to the pointer 147, and the scale 396, suitably attached to the bracket 364, is similar to the scale 148, and their operation and use are the same as previously described.

Referring to Fig. 12, an alternate arrangement is shown in which the bore of the cylinder 1 may be extended as into the head plate 397, provided with the water jacket 398, to contain the supplemental clearance volume varying means such as the piston 399, provided with the piston rings 400, 401, and the rod 402, to be operated and controlled in a similar manner as the pistons 53, 57, above described. The passage 403 corresponds to the passages 198, 199, 200, and the passage 404 to the passage 198, 199, 200, and the passage 404.

- may correspond to the passages connecting with pipes 19, or 111, or with the pipes 201, 203 as will be understood from the accompanying drawings and the pertinent description.
5. Whereas I have described my invention by reference to specific embodiments thereof, it will be understood that many modifications and changes may be made without departing from the spirit of the invention.
10. I claim:
1. In a variable capacity compressor, the combination of a cylinder comprising a compression compartment, a piston reciprocable therein, power operated means for operating the said piston, inlet and discharge valves and openings, and means for varying the clearance volume in indefinite extent by increments or decrements supplemental to the normal clearance volume in response to variation of output of the compressor.
  2. In a variable capacity compressor, the combination of a cylinder comprising a compression compartment, a piston reciprocable therein, power operated means for operating the said piston, inlet and discharge valves and openings, and continuously operating means for varying the clearance volume in indefinite extents by increments or decrements supplemental to the normal clearance volume in response to variations of output of the compressor.
  3. In a variable capacity compressor, the combination of cylinder means comprising a plurality of compression compartments, piston means reciprocable therein, power operated means for operating the said piston means, inlet and discharge valves and openings, and means effective throughout the entire travel of each of the said piston means for varying the clearance volume in indefinite extents by increments or decrements supplemental to each normal clearance volume in response to variations of output of the compressor.
  4. In a variable capacity compressor, the combination of cylinder means comprising a plurality of compression compartments, piston means reciprocable therein, power operated means for operating the said piston means, inlet and discharge valves and openings, and continuously operating means for varying the clearance volume in indefinite extents respectively supplemental to each normal clearance volume responsive to variations of output of the compressor.
  5. The combination of a device, comprising cylinder means, piston means reciprocable therein, means for operating the said piston means, valve and opening means, and continuously operating means for varying the clearance volume supplemental to each normal clearance volume by progressively increasing indefinite increments or progressively decreasing indefinite decrements the said supplemental clearance volumes in response to variations of output of the compressor as by decrements.
  6. In a variable capacity compressor, the combination of cylinder means, piston means reciprocable therein, power operated means for operating the said piston means, inlet and discharge valves and openings, and means for varying the clearance volume supplemental to each normal clearance volume by progressively increasing indefinite increments or progressively decreasing indefinite decrements the said supplemental clearance volumes, to vary the delivered capacity and power continuously and gradually between predetermined fractional limits of capacity.
  7. In a variable capacity compressor, the combination of cylinder means, piston means reciprocable therein, power operated means for operating the said piston means, inlet and discharge valves and openings, supplemental clearance volume varying means comprising an indefinitely variable volumetric division and an unvariable volumetric division thereof, means for indefinitely varying the effective volume of the variable division thereof.
  8. In a variable capacity compressor, the combination of cylinder means, piston means reciprocable therein, power operated means for operating the said piston means, inlet and discharge valves and openings, supplemental clearance volume varying means comprising variable and unvariable fractional volumetric divisions thereof, means for effecting combinations of the said fractional divisions thereof and for indefinitely varying the effective volume of the variable volumetric division thereof by increments or decrements to vary the total supplemental clearance volume in indefinite extents.
  9. In a variable capacity compressor, the combination of a cylinder comprising one compression compartment, a piston reciprocable therein, power operated means for operating the said piston, inlet and discharge valves and openings, means for varying the clearance volume in indefinite extents by increments or decrements supplemental to the normal clearance volume, and power means for operating the said supplemental clearance volume varying means.
  10. In a variable capacity compressor, the combination of a cylinder comprising one compression compartment, a piston reciprocable therein, power operated means for operating the said piston, inlet and discharge valves and openings, means for varying the clearance volume in indefinite extents by increments or decrements supplemental to the normal clearance volume, and electrical means for operating the said supplemental clearance volume varying means.
  11. In a variable capacity compressor, the combination of a cylinder comprising one compression compartment, a piston reciprocable therein, power operated means for operating the said piston, inlet and discharge valves and openings, means for varying the clearance volume in indefinite extents by increments or decrements supplemental to the normal clearance volume, and fluid pressure means for operating the said supplemental clearance volume varying means.
  12. In a variable capacity compressor, the combination of cylinder means, piston means reciprocable therein, power operated means for operating the said piston means, inlet and discharge valves and openings, means for operating and for varying the clearance volume in indefinite extents by increments or decrements supplemental to each normal clearance volume, and means for controlling the operation of the said operating and supplemental clearance volume varying means in response to varying output of the compressor.
  13. In a variable capacity compressor, the combination of cylinder means, piston means reciprocable therein, power operated means for operating the said piston means, inlet and discharge valves and openings, means for varying the clearance volume in indefinite extents by increments or decrements supplemental to each normal clearance volume, means for operating the said supplemental clearance volume varying means, and means for controlling the operation

and the extent of operation of the said operating means and the said supplemental clearance volume varying means in response to variations of output of the compressor.

5 14. In a variable capacity compressor, the combination of cylinder means, piston means reciprocable therein, power operated means for operating the said piston means, inlet and discharge valves and openings, means for varying 10 the clearance volume in indefinite extents by increments or decrements supplemental to each normal clearance volume, means for operating the said supplemental clearance volume varying means, fluid pressure responsive regulator means, 15 and means jointly operated by the said fluid pressure responsive regulator means and by the said supplemental volume operating and varying

means for controlling the operation and extent of operation of the said operating means and the said supplemental clearance volume varying means.

15. In a variable capacity compressor, the combination of a cylinder comprising a compression compartment, a piston reciprocable therein, power operated means for operating the said piston at a substantially constant rate of speed, inlet and discharge valves and openings, 10 associated with the cylinder, and means to continuously and gradually vary the clearance volume, supplemental to the normal clearance volume of the cylinder, in accordance with the variations in demand of the output of the compressor. 15

EVERETT W. SWARTWOUT.
